UNITED STATES PATENT OFFICE.

PERCIVAL F. KING, OF VANCOUVER, BRITISH COLUMBIA, CANADA.

EXTENSIBLE COVER FOR AUTOMOBILES.

1,298,733.

Specification of Letters Patent.

Patented Apr. 1, 1919.

Application filed June 13, 1917. Serial No. 174,551.

To all whom it may concern:

Be it known that I, PERCIVAL F. KING, a citizen of the Dominion of Canada, residing at Vancouver, in the Province of British Columbia, Canada, have invented certain new and useful Improvements in Extensible Covers for Automobiles, of which the following is a specification.

This invention relates to an extensible canopy or top cover for an automobile or the like vehicle, and comprises the provision whereby the canopy and its supporting frame are retained within a suitable casing at the back of the vehicle and may at the will of the driver be projected upward from the back and thereafter extended forward and latched to the wind-shield.

The device comprises also the provision whereby the side curtain may be separately but similarly extended.

The invention is particularly described in the following specification, reference being made to the drawings by which it is accompanied, in which:

Figure 1 is an end elevation on the plane 1-1 in Fig. 3 and in the direction of the arrow, of the frame which carries the canopy and side curtains at the back of the machine, showing the provision whereby the canopy supporting frame is elevated, as indicated by dot and dash lines, to the required height above the body of the machine.

Fig. 2 is a vertical section of the same on the line 2-2 in Fig. 1 showing the supporting frame with its canopy as lifted and extended to the front end and connected to the wind-shield.

Fig. 3 is a plan and part section showing the canopy supporting frame as extended and connected to the wind-shield.

Fig. 4 is a part section showing the profile of the canopy and side curtain supports.

Fig. 5 is a part horizontal section showing the side curtain rollers.

Fig. 6 shows to a reduced scale the application of the device to a car, and

Fig. 2^a is an enlarged detail of the latch by which the front end of the supporting frame is connected to the wind shield.

In these drawings 2 represents the back of the vehicle body, 3 being the wind-shield at the front end of the same. Pivottally mounted on a common center at 5 on the middle of the back of the body and in the lower part thereof, are two levers 6, one

end of each of which is link-connected at 7 to a rectangular frame 8, 9, 10, the other end of each lever being counterweighted at 13 to reduce the lifting weight of the frame 60 and its connected parts. The sides 10 of the frame are vertically movable in guides 11 in a casing 12 which is removably attached in any suitable manner to the body of the vehicle. 65

This vertically slidable frame carries the canopy and side curtains and the extensible supporting frame by which the canopy is carried forward and latched to the wind-shield. It is elevated to the position from 70 which the canopy is extended by lines 40 connected at 41 to the free end of the levers 6, which lines are carried under the car to the front end to be operable in any approved manner by the driver. 75

Slidably mounted on the top rail 9 of the rectangular frame are members 17 on the underside of which members are mounted grooved rollers 18 which bear against a supplementary bar 19 secured to the frame 80 to support the members 17 against rotation on the bar 9.

Pivottally connected at 20 to the upper side of the members 17 is a system of lazy-tong levers 21, the opposite end of which 85 system is connected to members 22 which are endwise movable on a bar 23. To this bar 23 is secured a front rail 24 to which is attached the front end of the canopy 25, to be described later, after it passes over a 90 rail 26 which supports it clear of the slideable members on the bar 23. Beyond the limit of movement of the slideable members 22 members 27 extend between the bar 23 and the front rail 24, which are designed 95 to rest upon the upper edge of the wind-shield 3 and adjacent these members a latch 28 is mounted on the bar 23 to engage the front edge of the wind-shield and thereby connect the canopy support to the shield. 100

The canopy 25, of any suitable light rain-proof material, is wound on a spring roller 30, the axle of which is mounted on brackets 31 rearwardly projecting from the upper part of the side members 10 of the rectangular frame. The spring 29 of this roller imposes a tension on the canopy and maintains it normally at the backward limit of its movement, that is, wound on the roller. 105

The canopy 25 is supported intermediate 110 of the front rails 24, 26 and the roller on thin cross strips 32 which are connected at

33 to the middle line pins of the lazy-tong lever system. These cross strips are curved downward at the ends, somewhat as shown in Fig. 4, to give the required watershed, 5 and the downwardly turned ends are looped, as at 34, to provide supports for two flexible lines 35 between the ends of the back bar 9 and the front bar 23, between which lines the upper edge of each side curtain 36 passes.

10 To support the canopy 25 clear of the slidable members 17 of the lazy-tongs on the bar 9, a rod 37 is carried above that bar and is curved approximately to the curvature of the canopy support strips 32, and to facilitate movement of the canopy over this rod a series of rollers 38 are independently rotatable on it, the length of which rollers is reduced on the curved ends.

20 When the slidable frame 8, 9, 10 with its connected mechanism is lifted by the lines 40 to the required height above the body of the vehicle, the canopy and its supporting frame are held by the spring 29 of the canopy roller 30 at the backward limit of their movement, in which position the slidable members 17 of the lazy-tongs are at the outer limit of their movement on the bar 9.

25 Flexible lines 42 are independently connected to the inner side of each slidable member 17 by which these members may be drawn together to project the supporting frame toward the front end of the car, against the resistance of the spring roller, and to the outer side of each member 17 similar lines 43 are connected by which these members may be drawn apart to retract the supporting frame, the spring of the roller, 30 winding the canopy itself upon the roller. These lines 42 and 43 pass over sheaves and 40 along the underside of the car body to the front end, where a suitable mechanism is provided by which the extension or retraction of the canopy may be effected by the driver, which mechanism will preferably be operated from the self-starter of the engine.

50 To counteract the tension of the canopy 25 on the upper side of the lazy-tong canopy supporting frame, tending to distort that frame upward, two flexible tapes 46 are connected to the front end of the canopy frame and pass under that frame to be wound on the roller 30 along with the canopy.

55 Rotatably mounted on vertical axes adjacent and parallel to each side 10 of the rectangular frame is a roller 47 having an internal coil spring 48, on which roller is wound a side curtain 36. Across the width of each side curtain a series of relatively rigid strips 49 are secured at intervals apart. 60 The ends of these strips project slightly beyond the upper and lower edges of the curtain, the lower ends to run in a grooved track 50 which is carried along each side of the car and across the doors, adjacent the upper edge of the body, and the upper ends pass

between the two flexible lines 35 carried by the ends 34 of the canopy support. The spring of the roller 47 tends to wind its curtain and retain it at the inner limit of its movement, and the curtain may be drawn out by hand and secured at any desired position of extension by any suitable means. 70

The device provides a convenient and readily operable means for supporting and extending a canopy and side curtains from 75 the back to the front of an automobile or the like, and one which can be operated by the driver whether the car is at rest or running.

80 Although the cover supporting frame is described and illustrated as extensible to the front end and latching to the wind-shield of the car, provision may obviously be made whereby it may be extended to shelter a portion only of the seating accommodation of 85 the car.

85 I do not desire to be confined to the particular construction of the several parts of the device, particularly as regards the back frame and its manner of elevation as the same may be modified without departing 90 from the substance of the invention.

95 Having now particularly described my invention, I hereby declare that what I claim as new and desire to be protected in by Letters Patent, is:

1. An extensible cover for an automobile or the like comprising a horizontally disposed lazy-tong system of levers adapted to project over the top of the vehicle and connected at one end to members which are slidable endwise on a bar that is disposed horizontally across the rear of the vehicle, said lazy-tong levers at the other end having provision for connecting it to the wind shield, a flexible fabric wound on a roller mounted across the rear of the vehicle, the free end of the fabric being connected to the front end bar of the lazy-tong system, means operative on the lazy-tong levers for extending 100 the same, means for retracting said levers, and means for winding the fabric on the roller as said lazy-tong levers are being retracted. 105

110 2. An extensible cover for an automobile or the like, comprising a lazy-tong system of levers connected at one end to members slidable endwise on a bar across the rear of the vehicle and having at the other end provision for connecting it to the wind-shield, 115 a cover supporting strip connected to each mid-pivot of the lazy-tong levers and extending across the width of the vehicle, flexible lines connected to the end bars of the lazy-tong levers and passing through the ends 120 of the supporting strips, a flexible fabric wound on a roller mounted at the rear of the vehicle the free end of the fabric being connected to the front end bar of the lazy-tong system of levers, means for project- 125 130

- ing the lazy-tong frames to the front end of the vehicle, means for securing it at that end, means for retracting the frame, and means for winding the cover on the roller as the frame is retracted. 5
3. An extensible cover for an automobile or the like, comprising in combination, a frame connected to the rear of the vehicle body and susceptible of being lifted there- 10 above, two members slidably mounted to move endwise on the upper rail of the frame, a lazy-tong system of levers pivotally connected at one end to the members slidable on the bar, and at the other end pivotally connected to similar members slidable on a front bar, a spring-actuated roller rotatably mounted on the rear frame, a flexible cover wound on the roller the free end of the cover being connected to the front end bar of the 15 lever system, means for simultaneously moving together the slidable members on the rear frame to project the front end bar, means for latching the front end bar to the wind-shield, and means for moving apart 20 the slidable members to retract the front end bar. 25
4. An extensible cover for an automobile or the like, comprising in combination, an open rectangular frame vertically slidable 30 in a casing secured to the after end of the body of the vehicle, a horizontally disposed extensible canopy supporting frame connected to the upper part of the slidable frame and susceptible of extension and at- 35 tachment to the front end of the vehicle, a roller rotatably mounted in the upper part of the slidable frame, a flexible canopy mounted on the roller, the free end of which canopy is connected to the outer end of the 40 extensible frame, means for lifting the slid- able frame, means for extending the sup- porting frame, means for retracting the sup- porting frame, and means for rolling the curtain on the roller as the supporting 45 frame is retracted. 5
5. An extensible cover for an automobile or the like, comprising an extensible frame connected to the after part of the vehicle and susceptible of being extended and se- 50 cured to the wind-shield, a flexible fabric cover wound on a spring-actuated roller, the free end of said cover passing over the upper side of the extension frame and at- tached to the front end of the same, and
- flexible tapes wound on the roller with the 55 cover, the free ends of which tapes are connected below the extension frame to the outer end of the same. 6
6. An extensible cover for an automobile or the like, comprising an open rectangular frame vertically slidable in a casing secured to the after end of the body of the vehicle, levers pivotally mounted on the body at the rear of the vehicle and link-connected on each side to the lower part of the frame, by 65 which levers the upper part of the frame may be projected above the body, an ex- tensible supporting frame connected to the upper part of the frame and susceptible of extension and attachment to the front end of 70 the vehicle, a roller rotatably mounted in the slidable frame, a flexible cover mounted on the roller the free end of which cover is connected to the front end of the exten- 75 sible frame, a spring-actuated roller ro- tatably mounted to turn on a vertical axis parallel and adjacent each side member of the slidable frame, side curtains mounted on these rollers, provision extending along the body supporting the lower edge of each cur- 80 tain, and provision connected to the exten- sible supporting frame for supporting the upper edge of each curtain. 85
7. In a mechanism of the class described, a supporting standard, a bar across said standard, a lazy-tong lever, members slid- able along said cross bar to which the adja- cent extremities of said lazy-tong levers are pivoted, a guide rod disposed parallel to said cross bar, and engaged by said slide mem- 90 bers to sustain said slide members with the lazy-tong levers in a horizontal position. 95
8. An extensible cover for automobiles and the like, comprising a lazy-tong system of levers connected at one end to members 100 slidably endwise on a bar horizontally dis- posed across the rear of the vehicle and hav- ing at the other end provision for connecting it to the wind shield, said slidable members having guide rollers, and a guide rail dis- posed parallelly to said cross bar and en- gaged by said rollers to sustain the lazy-tong levers in a horizontal position and a flexible fabric covering supported by the aforesaid structure. 105

In testimony whereof I affix my signature.

PERCIVAL F. KING.
